W. S. KUPFER.
SUPERPOSED DRIER AND KILN.
APPLICATION FILED APR. 23, 1920.

1,369,285.

Patented Feb. 22, 1921.

UNITED STATES PATENT OFFICE.

WALTER S. KUPFER, OF NEW YORK, N. Y., ASSIGNOR TO AMERICAN DRESSLER
TUNNEL KILNS, INC., OF NEW YORK, N. Y., A CORPORATION OF NEW YORK.

SUPERPOSED DRIER AND KILN.

1,369,285.

Specification of Letters Patent. Patented Feb. 22, 1921.

Application filed April 23, 1920. Serial No. 375,926.

To all whom it may concern:

Be it known that I, WALTER S. KUPFER, citizen of the United States, and resident of New York, in the county of New York and State of New York, have invented certain new and useful Improvements in Superposed Driers and Kilns, of which the following is a specification.

The general object of the present invention 10 is to provide a simple and effective combination of a continuous tunnel kiln and a continuous drier in which the drier is located above the kiln.

The various features of novelty which 15 characterize my invention are pointed out with particularity in the claims annexed to and forming a part of this specification. For a better understanding of the invention, however, and the advantages possessed by it 20 reference should be had to the accompanying drawings and descriptive matter in which I have illustrated a preferred embodiment of my invention.

Of the drawings;

25 Figure 1 is an elevation taken on the broken line 1—1 of Fig. 2.

Fig. 2 is a section taken on the line 2—2 of Fig. 1;

30 And Fig. 3 is a section taken similarly to Fig. 1 illustrating a modified construction.

In the drawing and referring first to the construction shown in Figs. 1 and 2, A represents a continuous tunnel kiln of the well known Dressler type. The kiln chamber is 35 provided at one end with an entrance door A¹ and at the opposite end with an exit door A². The kiln is heated by combustion chambers B located in the kiln chamber at opposite sides of the pathway for the brick 40 or other goods to be fired which are transported through the kiln on trucks or cars G running on the usual track rails provided on the floor of the kiln chamber. Combustible gas is admitted to the combustion chambers at, or adjacent one end as by burner 45 pipes C, and air to support combustion is admitted to the combustion chambers from the kiln chamber proper through inlets C¹. The products of combustion passes out of 50 the combustion chambers at their ends opposite to those at which combustion is initiated, through tubular extensions D of the combustion chamber into headers D' adjacent the entrance end of the kiln, and pass 55 out of the headers D' through an outlet D².

In line with the combustion chambers and adjacent the exit end of the kiln are a series of goods cooling pipes E through which atmospheric air is drawn from inlets E¹ in the kiln wall at the exit end of the kiln, to the 60 headers E², for the pipes E, adjacent the combustion chambers. The air passing through the pipes E and thereby heated is withdrawn from the headers E² through outlet channels E¹ and E² by a fan O.

In the construction shown in Fig. 2, there are two drying chambers H, placed side by side above the kiln A. Each drying chamber H is provided with an entrance door H¹ at one end and an exit door H² at the opposite 70 end. Between the track rails in each of the drying chambers for the goods carrying cars G, is located a conduit K, advantageously formed out of sheet metal. At the exit ends of the drying chambers the conduits K are both connected to the piping D² through which products of combustion escape from the flues D. Adjacent the entrance ends of the drying chambers the two 75 conduits K are connected to a cross conduit K¹ running to the stack L shown. The draft creating effect of the stack may be augmented by the action of a fan. The floor of drying chambers H is formed with ports H³ distributed along the length of the structure, except for a section adjacent the entrance ends of the chambers where the floor is imperforate. Air heated by contact with the outer walls of the kiln A and the piping 80 D² and E², and hot gases, if any, leaking out of the kiln chamber through the walls of the kiln passes into the drying chambers through the ports H³. To insure an effective use of this available waste heat in the drying chambers, I provide a petticoat like 85 housing H¹⁰ about the kiln and separated at the sides of the latter from the kiln walls by an air space through which atmospheric air, entering the space between the housing H¹⁰ and the kiln through the ports or opening 90 H¹¹ provided at the bottom of the housing H¹⁰, may pass upward along the walls of the kiln and eventually pass into the drying chambers through the ports H³. The petticoat housing H¹⁰ may be formed of sheet 95 metal or the like, and be suspended from the floor of the drying chambers. Dampers M may advantageously be provided for the ports H³ especially for those nearest the entrance ends of the drying chambers.

The air drawn through the cooling pipes E of the kiln A and thereby heated is utilized in the drying chambers. The means shown for distributing this air in the drying chambers comprises supply pipes P running longitudinally of the drying chambers along the floor of the latter except for a portion thereof immediately adjacent the entrance ends of the drying chambers. One of the pipes P runs along the dividing line between the two chambers H, while the other pipes P run along the remote sides of the two drying chambers. Each of the pipes P is provided with a series of upstanding branches P¹ which are connected at their upper ends to a corresponding series of horizontal pipe sections P² provided with small discharge orifices distributed along their lengths. The pipes P² are located at about the level of the tops of the goods supporting platforms of the cars G. Preferably the pipes P² are provided with regulating valves P⁴ which may be adjusted automatically or manually, as required to maintain the desired drying conditions in the chambers H. The latter are provided with roof outlets H¹⁵ for air and moisture, distributed along the portions of the driving chambers into which air is supplied through the ports H³ and the pipes P². The pipes P are connected to the outlet of the fan O.

At each end of the kiln and drier structure, provisions are made for handling the cars entering and leaving the different chambers at that end. The means shown at each end of the structure for this purpose comprises an elevator I which may be constructed like an ordinary freight elevator, and has tracks for a transfer table J movable transversely of the chambers to enable a car mounted thereon to be brought into alignment with the different chambers or into alignment with other tracks at the sides of the chambers.

In the contemplated mode of operation of the apparatus shown in Figs. 1 and 2, cars loaded with green ware are inserted alternately in the two chambers H at the entrance ends of the latter, and are moved slowly through the drying chambers, a car being removed from each drying chamber at its exit end as often as a car is inserted at the opposite end of the chamber. Each car of dried goods withdrawn from a drying chamber and placed on the transfer table J at the exit end of the driving chambers is next lowered to the level of the kiln chamber and is then moved into the latter. As often as a car is inserted at the entrance end of the kiln chamber, a car of finished goods is withdrawn from the exit end of the kiln chamber. With the two drying chambers operating in conjunction with a single kiln chamber of the same length, the rate of travel through the kiln chamber must be twice as

rapid as the rate of car travel through either drying chamber. I have not thought it necessary to illustrate means for pushing the cars into the drying chambers and the kiln chamber and advancing the trains of cars normally filling the different chambers, as various forms of car pushers suitable for the purpose are well known and in common use in conjunction with continuous tunnel kilns.

As each car of goods is moved through one or the other of the two drying chambers H it is gradually warmed, but without any appreciable removal of surface moisture until it reaches the portion of the drying chamber into which air is admitted through the floor ports H³ or through the pipes P². From then on the heating and drying action becomes more vigorous, and when the car reaches the exit end of the chamber the goods are thoroughly dried. In its passage through the kiln, each car of brick or other goods is further heated up until the goods are thoroughly burned, and is then cooled in its passage through the cooling zone of the kiln, partly by the air in direct contact with the goods leaking into the kiln chamber around the exit door of the kiln, or entering through ports specially provided for the purpose at the exit end of the kiln and eventually drawn into the combustion chambers, and partly by the air flowing through the cooling tubes E.

The arrangement disclosed in Figs. 1 and 2 obviously forms a simple and effective combination of a continuous tunnel kiln and continuous drier in which the available waste heat from the kiln is effectively utilized in the drying operation. The arrangement of a continuous drier above a continuous tunnel kiln possesses certain special advantages in that it permits the products of combustion from the chamber and the hot air from the cooling zone of the kiln chamber to be passed into the drying chambers at appropriate points by short and simple piping and with practically no waste of heat from this piping. A further advantage is that it permits of an effective utilization of the heat otherwise lost from the kiln by radiation from its outer walls or leakage through those walls to be effectively utilized in the drier.

Those skilled in the art will also understand that in the manufacture of bricks, hollow tile, and the like it is a great advantage, in many cases, to carry on the manufacture and burning of the brick on different floors. This simplifies the problem of keeping the unfinished products apart from the finished products and reduces the ground space required for the plant.

It will, of course, be obvious that instead of two drying chambers above the tunnel

5 kiln, it may be advantageous in some cases to have more than two drying chambers, and in other cases to have only a single drying chamber, and in Fig. 3 I have shown
 10 a construction in which there is a single drying chamber HA located centrally above the kiln chamber. Aside from the omission of one drying chamber and corresponding portions of the piping, the apparatus shown in Fig. 3 need not differ from that shown in Figs. 1 and 2, and requires no additional description.

15 While, in accordance with the provisions of the statutes, I have illustrated and described the best form of my invention now known to me, it will be apparent to those skilled in the art that changes may be made in the form of the apparatus disclosed without departing from the spirit of my invention as set forth in the appended claims, and that certain features of my invention may sometimes be used to advantage without a corresponding use of other features.

20 Having now described my invention, what I claim as new and desire to secure by Letters Patent, is:

25 1. The combination with a continuous tunnel kiln, of a continuous drier located above the tunnel kiln, and having its exit end adjacent the entrance end of the kiln, and goods carrying cars movable successively through the drier and kiln.

30 2. The combination with a continuous tunnel kiln, of a continuous drier located above the tunnel kiln, and having its exit end adjacent the entrance end of the kiln, goods carrying cars movable successively

first through the drier and then through the kiln, and provisions for utilizing the waste heat of the kiln in heating and drying the 40 goods passing through the drier.

3. The combination with a kiln, of a drier and a means for utilizing in the drier air heated by passage along the outer side of the wall of the kiln.

4. The combination with a kiln, of a drier located above the kiln, and means providing an air space about the kiln with air inlets at its lower end and opening at its 50 top to said drier.

5. The combination with a continuous tunnel kiln, of a continuous drier above the tunnel kiln, the kiln and drier each having its entrance end adjacent the exit end of the other, goods carrying cars movable 55 successively through the drier and kiln, and elevators at each end of the kiln and drier for moving said cars between the kiln and drier levels.

6. The combination with a continuous tunnel kiln having an outlet for products of combustion at one end and an outlet intermediate its ends for air used in cooling goods in a cooling zone of the kiln, of a continuous drier located above the kiln 65 and provided with a longitudinal heating conduit connected at one end to the first mentioned outlet, and provided with air distributing conduits connected to the second mentioned outlet.

70 Signed at New York, in the county of New York and State of New York, this 21st day of April, A. D. 1920.

WALTER S. KUPFER.
